(57) **CLAIM**

The ornamental design for an iris scanning orb as shown and described.

DESCRIPTION

FIG. 1 is a front view of the iris scanning orb showing a front face of the iris scanning orb;

FIG. 2 is a left side view of the iris scanning orb, of which the right side view is mirrored.

FIG. 3 is a perspective view showing a portion of the iris scanning including the front face;

FIG. 4 is a perspective view of the iris scanning orb showing a bottom and back of the iris scanning orb;

FIG. 5 is a bottom view of the iris scanning orb; and,

FIG. 6 is a partial bottom view of the iris scanning orb. Broken lines are used in the drawings to illustrate features of the iris scanning orb that form no part of the claimed design.

1 Claim, 6 Drawing Sheets
